UNITED STATES PATENT OFFICE

MALCOLM S. JOHNSON, OF CHICAGO, ILLINOIS, ASSIGNOR, BY MESNE ASSIGNMENTS, TO
ILLINOIS RAILWAY EQUIPMENT COMPANY, A CORPORATION OF ILLINOIS

BRAKE HANGER

Application filed November 6, 1929. Serial No. 405,090.

My invention relates to hangers for the brake shoes of railroad cars; the invention having for its object the provision of hangers adapted to standard truck frame construction and possessing greater strength than the hangers heretofore employed, while at the same time providing hangers which may be made without substantial increased cost of manufacture and at the same time being materially strengthened to withstand the wear and strains to which brake hangers are subjected.

The objects and advantages of my invention will be readily comprehended from the detailed description of the accompanying drawings, wherein—

Figure 1 is a side elevation of a portion of a truck side frame and car-wheel, showing one form of my improved hanger in brake-shoe supporting position.

Figure 2 is a detail view of the hanger in front elevation, with portions of the bracket and brake-shoe lugs shown in section.

Figure 3 is a detail view in elevation of the hanger shown in Figures 1 and 2, as viewed in Figure 1.

Figure 4 is a view similar to Figure 2, illustrating a modification of the type of hanger shown in the preceding figures.

Figure 5 is an elevational view of the hanger as viewed at right angles to Figure 4.

Figure 6 is a top end view of the hangers shown in Figure 2 and in Figure 4.

Figure 7 is a view similar to Figures 2 and 4, illustrating a modified form of hanger.

Figure 8 is a side elevation of the hanger, as viewed at right angles to Figure 7.

Figure 9 is a cross sectional view taken substantially on the line 9—9 of Figure 7 as viewed by the arrows.

My improved brake hangers are intended for use with the standard accepted type of truck side frame provided with brackets shown at 15 in Figure 1 and consisting of transversely slotted lugs adjacent to the vertical compression members, one of which is shown at 16 in Figure 1.

The slots or pockets 17, intermediate of the upper and lower portions of each lug, are adapted to receive the upper ends of the

brake-shoe hangers, in conjunction with suitable means for retaining the hangers in place.

As my present invention relates to the hangers per se, further detailed description of the bracket and keeper element need not be entered into.

In Figures 1 to 3, inclusive, I have shown one form of my invention in the nature of what is known as the continuous or closed link type having the two elongated parallel sides 18, 18 united at their ends by the integral end portions 19 and 20. The sides 18 and the upper end 19 are usually circular in cross-section; the upper end 19 being seated in a groove formed in the lower portion or lug of bracket 15 so as to permit the hanger with the brake-shoe to swing toward and away from the truck-wheel.

In order to provide the hanger with a wide bearing surface against the sides of the bracket or keeper elements arranged in the support or bracket, I provide the upper end of the hanger with the integral portions or lobes 21, 21, which are made substantially circular, as shown in Figures 1 and 3, and extend beyond the normal plane of the hanger; that is to say, these enlarged portions or lobes 21 extend laterally beyond the sides 18, 18 and upwardly beyond the upper end 19.

These portions or lobes 21, 21 are made with substantially flat inner faces so as to lap the opposite sides of the bracket 15, as shown in Figure 2; the sides 18, at their upper ends, tapering toward the portions 21, 21 above the upper end 19 to provide reenforcing ribs 22.

With my improvement, a very much stronger hanger is provided than heretofore has been the case, as my hanger is of materially greater strength at a point where it encounters the greatest wear, namely at the curved upper end where the strains are encountered.

In order to provide a self-locking hanger in its relation with the shoe, I show the lower end 20 oblong in cross-section, namely with its opposite vertical sides substantially flat, as shown in Figure 3. This permits the hanger to be inserted into an undercut slot in the shoe head so that when the shoe and

hanger are in normal operative position, dissociation of the hanger and shoe head will be impossible.

In Figures 4 to 6, inclusive, I show a modification of the hanger previously described, in that the lower end 23, like the upper end 19, is also provided with the side enlargements or portions 24, 24, similar to the upper enlargements 21, 21. That is to say, in Figures 4 and 5, I show both ends of the hanger provided with the wide bearing surfaces which are reinforced by the ribs 22 which extend longitudinally of the sides 18 of the hanger and thus greatly reinforce the wide bearing surfaces which extend beyond the main body portion of the link or hanger at points where the wear and strains are encountered.

The lower end 23 of the hanger shown in Figures 4 and 5, like the lower end 20 of the hanger shown in Figures 1 to 3, is also preferably provided with the flat vertical sides for the purpose heretofore mentioned.

The forms of hangers thus far described are particularly intended to be of the cast metal type, with the portions receiving the wear and strains materially strengthened and wide bearing surfaces provided at opposite sides of the link.

In Figures 7 to 9, inclusive, I illustrate another modification of my invention as applied to the U-type of link or hanger, which may be a drop forging and therefore more cheaply made and which consists in converting a U-shape hanger into a continuous link.

In carrying out this modification of the invention, a forged U-shape link 25 having enlarged apertured ends 26, 26 is employed; while the lower or closed end 27 is preferably flattened, as previously described. The inner faces of the enlarged apertured ends 26 are countersunk about the apertures, as shown at 28, to receive the ends of a sleeve or bushing 29 having a bore substantially the size of the apertures in the enlarged ends 26 for the purpose of receiving the pin or rivet 30, see Figures 7 and 9.

With the main part of the hanger a forging, the arms or sides of the hanger may be slightly sprung or spread apart to permit the bushing or sleeve 29 to be inserted into the countersunk portions 28 about the apertures.

After the bushing or sleeve 29 has been sprung into place, I then insert the pin or rivet member 30 through the apertures of the U-shape link and through the sleeve 29 and upset or rivet the ends in place, as shown at 31, thereby firmly holding the sleeve in place and providing a continuous link with wide bearing faces on opposite sides of the bracket in which the hanger is suspended.

It is also apparent, that in the event the sleeve 29 becomes worn, it may be replaced upon removing the rivet 30 and spreading the hanger sides apart, thereby permitting a

new sleeve to be inserted and employing a new pin or rivet, thus obviating the necessity of discarding the entire link.

With my invention, brake hangers having wide bearing faces for bearing against the sides of the keeper elements or brackets are provided while at the same time hangers having greater strength than is the case with hangers as heretofore employed and therefore hangers possessing a greater period of usefulness.

What I claim is:

1. A brake hanger comprising an elongated substantially U-shape link having apertured enlarged ends, the inner opposing faces of said enlarged ends being countersunk about the apertures, a sleeve of length slightly larger than the normal distance between the ends of the link, the ends of the sleeve being seated in the countersunk portions of the ends, and locking means disposed through the apertured ends and through said sleeve whereby the link-ends and the sleeve are rigidly secured together into a continuous hanger.

2. A brake hanger composed of an elongated U-shape link provided with enlarged apertured ends, the inner opposing faces of said enlarged ends being counter-sunk about the apertures, a sleeve disposed between said ends with the sleeve-ends seated in the countersunk portions, and a rivet disposed through said apertured ends and the sleeve.

MALCOLM S. JOHNSON.
